DESIGN FOR A COMBINED BOTTLE SUPPORT AND DISPLAY CABINET

Paul A. De Sabato, Pittsburgh, Pa.

Application July 9, 1938, Serial No. 78,367

Term of patent 7 years

To all whom it may concern:

Be it known that I, Paul A. De Sabato, a citizen of the United States, residing at Pittsburgh, in the county of Allegheny and State of Pennsylvania, have invented a new, original, and ornamental Design for a Combined Bottle Support and Display Cabinet, of which the following is a specification, reference being had to the accompanying drawing, forming part thereof.

In the drawing:

Fig. 1 is a perspective view of the combined bottle support and display cabinet, showing my new design;

Fig. 2 is a cross-sectional view thereof on the line II—II of Fig. 1.

I claim:

The ornamental design for a combined bottle support and display cabinet, as shown.

PAUL A. DE SABATO.
